TOY PROPELLER AND TOP

Oliver H. Bennett, Jamestown, N. Dak.

Application December 20, 1933, Serial No. 703,295

2 Claims.

(Cl. 46—32)

This invention relates to an improved combined toy propeller and top.

One object of the invention is to provide a device of this character wherein the propeller employed will be supported in such a manner that it will be permitted to ascend vertically after a spinning operation.

One object of the invention is to provide a combined toy propeller and top employing a fly-wheel which is detachable for permitting the top to spin on the floor.

Another object of the invention is to provide a combined toy propeller and top utilizing the fly-wheel in connection with the top so that a greater revolving speed may be imparted to the propeller to permit its staying in the air or against the ceiling of a room for a relatively long period of time.

A further object of the invention is to provide a combined toy propeller and top, the propeller of which is so formed that it will not be permitted to slip sideways during its ascension, thus retaining the top in a relatively small area.

A further object of the invention is to provide a combined toy propeller and top wherein the propeller is detachable along with the fly-wheel for permitting independent spinning of the top and release thereof from the handle.

And a still further object of the invention is to provide a device of this character which will be characterized by the utmost simplicity and which will provide a highly pleasing entertainment for children.

Still further and incidental objects of the invention, not specifically enumerated in the foregoing, will be apparent as the description of the invention proceeds.

My invention is illustrated in the accompanying drawing, wherein

Figure 1 is a vertical sectional view showing my device as it would appear ready for use, a portion of the handle employed being shown in elevation,

Figure 2 is a top plan view of my device,

Figure 3 is a top plan view of the fly-wheel employed, and

Figure 4 is a plan view showing the top as it would appear detached from the handle.

Referring now more particularly to the accompanying drawing wherein like numerals of reference designate like parts throughout the several views, the numeral 1 indicates in general the handle of my device which is formed of wood or other suitable material. The handle is enlarged at its inner end to provide a body 2 which is cut away to define a yoke 3 having spaced parallel arms 4 and 5.

Rotatably and detachably mounted on the yoke is a top which is indicated generally by the numeral 6. The top includes a stem 7 which extends through the arms 4 and 5 at right angles thereto and near their outer ends. The stem is of sufficient length so that its upper end terminates a slight distance past the outside of the arm 4. Formed in the stem and adapted for disposal near the inner face of the arm 4 is an opening 8 extending at right angles to the length of said stem. 10 The stem carries a disk 9 which is substantially semi-elliptical in vertical cross section. The disk is mounted on said stem so that the lower end of the stem projects below the disk to provide a spinning point for said top. It should be understood that the stem is mounted in the yoke so as to be freely rotatable and readily detachable therefrom. The top may be formed of wood, light weight metal, or other suitable material.

Detachably secured to the upper end portion 20 of the stem 7 is a fly-wheel 10, which is formed of a relatively heavy metal. The fly-wheel is detachably secured to the stem by means of a set screw 11. Formed in the face of the fly-wheel is a square socket 12. The fly-wheel is adapted to be 25 mounted to rotate with the stem and disk. The stem is provided with a spinning string 13 which is, as shown in Figure 1, wound about the stem 7 between the arms 4 and 5 of the yoke with its inner end extending through the opening 8 and 30 removably anchored therein. A ring 14, for manual engagement, is provided on the outer end of the string. It will be understood that the unwinding of the string 13 from the stem 7 will cause rapid rotation of said stem which will, of 35 course, be imparted to the disk and to the fly-wheel. When the fly-wheel is not employed and the device used merely as a handle and top, and the string has been released, the stem of the top will be permitted to drop through the yoke to a 40 floor or other surface upon which it will be permitted to spin until it runs down.

Detachably mounted on the handle is a propeller 15. The propeller is provided with a circular depending flange 16 and blades 17 which 45 are bent obliquely. The entire propeller may be formed from a single piece of sheet metal and stamped and bent into shape. The propeller is provided axially thereof with a hub 18 having a squared lower end 19 which is adapted to fit detachably within the socket 12 in the fly-wheel 10. The upper end of the hub is formed to define a point 20 which is adapted to impinge on the ceiling of a room, or the like. As best seen in Figure 1, the lower end of the squared portion 19 of 50 55

the hub is slightly pointed so that the propeller may spin thereon.

It will be understood that after the top and fly-wheel have been rotated by unwinding the string 13 from the stem 7 thereof, the propeller will be spun at a high speed and will become disengaged from the socket in the fly-wheel and will ascend to the ceiling. The propeller will spin upon the ceiling until some of its momentum is lost, when it will gradually descend and spin upon the floor until completely run down.

Momentum imparted by the flywheel will cause the stem to continue rotation after the propeller rises and the string will be partially wound in a reverse direction upon the stem. Therefore, when a quick pull is exerted upon the string the stem will be rotated in the original direction and the string will be first unwound and then partially or entirely rewound upon the stem. It will thus be seen that the flywheel 10 will aid in rewinding the spinning string 13 after a spinning operation, and that by the time the stem stops rotating, the string will be completely wound thereon and will be ready to be spun again.

In view of the fact that I have employed the flange 16 in conjunction with the propeller, said flange will prevent lateral shifting movement so that the propeller will be permitted to ascend and descend substantially vertically. This flange will also prevent bending or breaking of the blades 17 and will tend to prevent damage to objects with which the toy may come in contact.

It should be understood that, if desired, the top and flywheel may be removed from the yoke and the flywheel then again fitted upon the stem close to the disk and the device used as a yo-yo toy.

It is believed that a reading of the foregoing description will render entirely apparent that I have provided a toy which will be highly amusing and at the same time durable and cheap in manufacture.

Having thus described my invention, I claim:

1. A convertible device of the character described, comprising a handle having a body formed with a yoke, a top having a stem rotat-

ably engaged through the yoke, a disk carried by the stem below the yoke, a weighted fly wheel of appreciably greater diameter than the stem detachably carried by the stem above the yoke and projecting upwardly therefrom whereby the upper portion of the stem receiving bore of the fly wheel forms a socket, a propeller having a central shank detachably engaged in the socket of the fly wheel, and a string adapted to be wound upon the stem between arms of the yoke and quickly unwound therefrom when pulled from its outer end for rotating the top whereby said propeller will be rapidly spun and projected upwardly from the socket of the fly wheel during the spinning operation.

2. A convertible device of the character described comprising a handle having a yoke at one end including upper and lower arms formed with aligned openings, a stem rotatably engaged through the openings in the arms of said yoke and projecting above and below the arms, a disk of appreciably greater diameter than the stem rigidly carried by the stem below the lower arm in spaced relation to the lower end of the stem, a weighted fly wheel detachably connected with the stem above the upper arm and formed with a center opening open at its upper end, the stem being releasably secured in the opening of the fly wheel with its upper end spaced from the upper end of the opening whereby the portion of the opening above the stem forms a socket open at its upper end, the said socket being non-circular in cross section, a propeller having a hub formed at one end with a spinning point and at its other end being reduced to form a shank loosely received in the socket of the fly wheel and conforming to the cross sectional shape thereof, said propeller having blades radiating from the hub and a rim about the outer ends of the blades, and a string adapted to be wound about the stem between the arms of the yoke and quickly unwound for rotating the top and propeller whereby disengagement of the propeller from the fly wheel and ascension of the propeller will take place.
